UNITED STATES PATENT OFFICE.

FRANK J. MATHEWS, OF DEER PARK, WISCONSIN.

CHURN TIMER.

Application filed April 8, 1919. Serial No. 288,483.

To all whom it may concern:

Be it known that I, FRANK J. MATHEWS, a citizen of the United States, residing at Deer Park, in the county of St. Croix and State of Wisconsin, have invented new and useful Improvements in Churn Timers, of which the following is a specification.

This invention relates to timing devices for use in connection with a cylinder mounted for rotation and controlled by a clutch mechanism, the device being especially adapted for use in connection with churning, for the purpose of automatically stopping their operation after a predetermined number of revolutions.

Another object of the invention is to provide a device of the above character which is capable of adjustment so that the number of revolutions of the cylinder may be regulated to suit various conditions.

Another object is the provision of a device which may be used in connection with mechanism irrespective of the direction of operation of the controlling clutch lever, rendering the device applicable to churning of different makes.

Other objects and advantages of the invention will appear as the description is read in connection with the accompanying drawings.

In the drawings:

Figure 1 is a side elevation of one end of a churn cylinder with the invention applied thereto and showing an operating mechanism in which the clutch lever operates in a direction toward the churn cylinder to stop the operation of the churn.

Figure 2 is an enlarged elevation of the invention removed from the churn and looking in a direction at right angles to Figure 1.

Figure 3 is a sectional view taken on a line with the tensioning device.

Figure 4 is a view similar to Figure 1, illustrating the invention applied to a churn, whose clutch lever operates in a reverse direction to that shown in Figure 1.

Referring to the drawings in detail, wherein like characters of reference denote corresponding parts, the reference character 10 denotes a cylinder of a churn, which is mounted to revolve horizontally through the medium of suitable operating mechanism, the said mechanism being controlled by a clutch lever 11. This lever Figure 1 is movable in a direction toward the cylinder

10 to release or stop the mechanism and in an opposite direction to throw in a clutch for the purpose of operating the churn.

The invention resides in a timing mechanism which is mounted upon a frame 12 of the churn in a position adjacent the end of the cylinder 10. This mechanism includes a frame 13, the lower arm of which is bolted, or otherwise secured to the frame 12, as shown at 14. The upper end of the frame is bifurcated to provide spaced arms 15, between which is mounted for rotation a spool 16. This spool is mounted upon a short shaft 17 and carries at one end a toothed wheel 18. The wheel 18 is positioned at right angles to and slightly spaced from the end wall of the cylinder 10 and is located in the path of movement of a projection 19, herein shown in the form of an L-shaped finger secured to the end wall of the cylinder 10.

Secured to the opposite end of the spool 16, is a ratchet wheel 20, the teeth of which are adapted to be engaged by a spring detent 21, secured upon the frame 13. This ratchet wheel and detent serve to limit the degree of rotation of the spool 16 at each engagement of the projection 19 with the toothed wheel 18. The spool 16 is connected to the clutch lever 11 through the medium of a flexible element 22, the latter being in the form of a cord or chain, having one end connected to the spool and its opposite end connected to the said clutch lever, so that when the flexible element has been sufficiently wound upon the spool, a pull will be exerted upon the lever 11 to disengage the clutch controlling operation of the churn mechanism. The length of time necessary for the operation of the churn may be controlled by regulating the length of flexible element 22 to be wound upon the spool, so that after a predetermined number of revolutions of the cylinder 10, the flexible element will become taut and a pull exerted upon the lever 11 and the rotation of the cylinder discontinued.

In order that the flexible element may be properly wound upon the spool, the frame 13 supports a tensioning device in the form of an arm 23, one end of which is secured to the said frame and the opposite end of which is formed into a spring clamp 24, which is adapted to yieldingly hold the flexible element taut between the tensioning device and the spool. Guide flanges 25 are provided

upon the opposite side edges of the clamp 24 to hold it in position.

In Figure 4 the invention is shown as applied to a churn mechanism, the controlling lever 26 of which operates in a direction reverse to that of the lever 11 previously described, or in other words is moved in a direction away from the cylinder 10 to stop the operation of the churn. To 10 accomplish this the flexible element which connects the lever and spool is threaded through a pulley 27, the latter being adjustably mounted upon an arm 28, as shown at 29. This arm is secured to the frame of 15 the churn, as shown at 30. The spool 16, may therefore be rotated in the same direction as the one previously described. The pull upon the inner portion of the flexible element 22 is exerted in a direction toward 20 the end of the churn, while the pull upon the outer end or the end connected to the lever 26, is exerted in an opposite direction, or away from the end of the churn.

In this form of the invention the frame 25 of the timing mechanism differs slightly from the frame 13, previously described. This difference resides in providing a substantially L-shaped frame 31, one end of which is bifurcated and supports the spool 30 16 in the usual manner and the opposite end is connected to the frame of the churn, as shown at 32.

It will be apparent that the functions of the various parts of the invention are similar in both forms shown, the changes being 35 mere matter of details to adapt the invention to different makes of churn.

The invention is susceptible of various changes in its form, proportions and minor details of construction and the right is 40 herein reserved to make such changes as properly fall within the scope of the appended claim.

Having described the invention, what is 45 claimed is:

The combination with a rotatably supported cylindrical churn having a clutch controlled operating means including a clutch lever, of a timing mechanism associated with the clutch and comprising 50 a frame having one end offset and secured to the churn supporting means, spaced arms formed on the opposite end of the frame, a short shaft having bearings in the ends of the arms, a spool secured to the shaft between the arms, a substantially L-shaped finger secured to one side wall of the churn, a toothed wheel carried by one end of the spool and lying in the path of the L-shaped finger to be rotated thereby, such rotation 55 being imparted to the spool, a ratchet wheel secured to the opposite end of the spool, a spring detent secured to the frame and having its free end arranged in the path of the ratchet wheel, an arm pivotally secured to the frame opposite the spring detent, a spring clamp secured to the free end of the arm and a flexible element passing through the spring clamp and being secured to the spool and clutch lever respectively as 60 and for the purpose specified.

In testimony whereof I affix my signature.

FRANK J. MATHEWS.
